UNITED STATES PATENT OFFICE.

JAMES E. ROWE, OF PAWTUCKET, RHODE ISLAND, ASSIGNOR TO E. JENCKES MANUFACTURING COMPANY, OF PAWTUCKET, RHODE ISLAND, A CORPORATION OF RHODE ISLAND.

KNITTING-MACHINE.

No. 806,293.

Specification of Letters Patent.

Patented Dec. 5, 1905.

Application filed January 6, 1902. Serial No. 88,508.

To all whom it may concern:

Be it known that I, JAMES E. ROWE, of the city of Pawtucket, county of Providence, and State of Rhode Island, have invented 5 certain new and useful Improvements in Knitting-Machines; and I do hereby declare the following specification, taken in connection with the accompanying drawings, forming a part of the same, to be a full, clear, and 10 exact description thereof.

The features of the invention relate to knitting-machines and may be employed with special advantage in circular-knitting machines adapted for use in knitting half-hose 15 or stockings, in which the needles are guided in grooves in a needle-cylinder and are operated to draw the loops in forming the stitches by a single knitting-cam carried by a cam-cylinder, one of the cylinders being 20 rotated during the formation of the leg and foot of the stocking and being reciprocated during the formation of the heel or toe. In such a machine the wave formed in the series of needles as they are moved in forming 25 the stitches travels about the series of needles and is in substantially fixed relation with the cam-cylinder both during rotary and reciprocating knitting. During the movement of the cam or needle cylinder, as 30 the case may be, in one direction the needles on one side of the knitting-wave will be moving down to draw the new loops through the loops on the needles, and the needles on the other side will be moving up through the 35 newly-drawn loops, while during the movement of the cam or needle cylinder in the other direction the movements of the needles in the knitting-wave are reversed, those on the side where the needles were moving up 40 now moving down and those on the side where the needles were moving down now moving up. It follows, therefore, that in a machine of this character, wherein the loops are held as the needles rise through them by 45 reciprocating sinkers, that the sinkers should be so operated that they will be withdrawn on one side of the knitting-wave and will be advanced on the other side of the wave as the wave travels in one direction, and when 50 the direction of travel of the wave is reversed the sinkers will be withdrawn on the side where they were advanced and advanced on the side where they were withdrawn in order

that the sinkers may, during the travel of the wave in each direction, be withdrawn 55 where the needles are acting to draw the new loops and be advanced on that side of the knitting-wave where the needles are rising through the newly-drawn loops.

The present invention relates to devices 60 for operating the sinkers or web-holders of a knitting-machine and is especially useful in the above character of machine in that it admits of a simple and efficient construction for operating the sinkers in the manner set 65 forth.

In a construction embodying the features of this invention the sinkers are retracted and advanced by cams which are shifted to vary the points at which the sinkers are operated. In case the invention is embodied in a machine in which the needle-cylinder rotates and the knitting-cams are fixed the sinker-cams will remain stationary, and the sinkers will travel with the needle-cylinder, 75 while in machines wherein the cam-cylinder rotates the sinker-cams will be mounted upon a sinker cam-ring which travels with the cam-cylinder.

A form of the invention well adapted for 80 use in knitting-machines of the character referred to is that shown in the accompanying drawings, and this form of the invention will be explained in detail in connection with the application to such a machine.

In the drawings, Figure 1 is a plan view indicating the manner of operating the sinkers as the cam-cylinder moves in one direction. Fig. 2 is a corresponding diagrammatical view indicating the manner of forming 90 the knitting wave and leading the thread to the needles. Fig. 3 is a view similar to Fig. 1 with the cam-cylinder moving in the opposite direction. Fig. 4 is a view similar to Fig. 2 with the cam-cylinder moving in 95 the opposite direction. Fig. 5 is a sectional elevation showing the manner of mounting and connecting various parts of the machine. Fig. 6 is a plan view of a part of the sinker cam-ring, showing the manner of mounting 100 the sinker-cams. Fig. 7 is a view looking at the bottom of the same part of the sinker cam-ring. Fig. 8 is a section on line 8 8, Fig. 7. Fig. 9 is a section on line 9 9, Fig. 7.

In the machine shown in the drawings the 105 needles 1 are guided in grooves formed in the

outer periphery of a needle-cylinder 2, being held in said grooves by spring-bands 3 in the usual manner. The needles are provided with the usual butts 5, through which they 5 are given their movements in the operation of the machine. The cams for operating the needles are carried by a cam-cylinder 6, provided with a gear 8, through which it may be given a continuous rotary movement or a reciprocating movement by any suitable mechanism such as is well known in the knitting art.

The needle-butts are supported upon an annular ledge 9, carried by the cam-cylinder, 15 and the knitting-cam for drawing down the needles and the coöperating cams for raising the needles are located at the ends of this ledge. The knitting-cam consists of a plate 11, provided with converging cam-surfaces 20 12 and 13, which engage the needle-butts and force them downward. The coöperating cams consist of inclined cam-surfaces 16 and 17, the surface 16 being parallel to the cam-surface 13 and the surface 17 being parallel 25 to the cam-surface 12. When the cam-cylinder rotates in the direction of the arrow, Fig. 2, the needle-butts pass down the surface 12, under the point of the knitting-cam, and up the surface 16. When the cam-cylinder rotates in the opposite direction during 30 reciprocating knitting, the needle-butts pass down surface 13, under the point of the knitting-cam, and up surface 17 onto the ledge 9. Thus the knitting-cam and coöperating cams 35 form a wave, as shown at 18, Figs. 2 and 4, in the series of needles which travels continuously around the series of needles during rotary knitting and back and forth across the series of active needles during reciprocating 40 knitting, the position of the wave with relation to the cam-cylinder being substantially fixed, since the lowest point of the wave is always formed by the point of the cam-plate 11.

45 The sinkers 19 for holding the fabric as the needles rise through the loops last drawn by them are mounted in radial grooves in a sinker-ring 19^a, secured to the needle-cylinder, and the forward ends of the sinkers are 50 guided in slots formed in the top of the needle-cylinder. The sinkers are provided with the usual hooks or fingers for overlying the fabric and are reciprocated in their guiding-grooves by cams carried by a sinker cam-ring 21, mounted to turn on the sinker-ring 19^a, 55 the cam-ring being provided with an annular rib 22, which fits over the outer edge of the sinker-ring and being held upon the sinker-ring by clips 23, engaging the under surface 60 of the ring. A guiding-ring 20, provided with radial grooves through which the sinkers pass, is mounted in the inner edge of the sinker-ring and is held down in position to prevent the rise of the sinkers by the sinker 65 cam-ring.

When the cam-cylinder is moving in the direction of the arrow, Fig. 4, the wave 18 is traveling along the needles in the same direction, and the needles on the right of the point where the loops are drawn or the knitting-point are moving downward and the needles on the left of the knitting-point are moving upward. When the cam-cylinder is moving in the opposite direction, as in Fig. 2, 70 the wave also travels in the opposite direction and the needles on the left of the knitting-point will be moving down and the needles on the right will be rising. It follows, therefore, that during the movement of the cam-cylinder from left to right the sinkers 80 should be withdrawn at the right of the knitting-point where the needles are drawing the loops and should be in advanced position at the left of the knitting-point where the needles are rising, as in Fig. 3, and that when the 85 cam-cylinder is moving from right to left the sinkers should be withdrawn at the left and advanced at the right of the knitting-point, as in Fig. 1—that is to say, the points at 90 which the sinkers are withdrawn and advanced should be shifted from side to side of the knitting-wave as the cylinder reciprocates.

The sinkers are held in their inner position with the hooks above the fabric by an annular rib 24 on the sinker cam-ring, which passes through grooves extending laterally through the upper edges of the sinkers. The rib 24 is interrupted opposite the knitting-wave, and between the ends of the rib are mounted the 95 cams for retracting and advancing the sinkers, the cams being so constructed and arranged that they are shifted to vary the points at which the sinkers are retracted and advanced. In the form of the invention 100 shown the cams consist of four cam-surfaces 25, 26, 27, and 28, formed on a movable plate 29, mounted between the ends of the rib 24. The plate 29 is mounted for movement on the under side of the sinker cam-ring by means of screws 30, which pass through slots 31 in the cam-ring and are provided with heads engaging the upper surface of the cam-ring. The ends of the rib 24 are 105 formed to fit the curved ends of the plate 29, 110 and the ends of the rib and plate are formed to overlap, so as to bridge over the space which would otherwise be left between one end of the plate and the adjacent end of the rib when the plate is shifted.

115 The plate 29 is so shaped and guided by the slots 31 that when the cam-ring is moving in the direction of the arrow, Fig. 1, the cam-surface 25 projects beyond the rib 24, and as it travels through the grooves in the 120 sinkers engages the outer ends of said grooves and retracts the sinkers. The retracted sinkers are then advanced by the cam-surface 26, which engages the inner ends of the 125 grooves in the sinkers and forces the sinkers 130

into their advanced position. At this time the cam-surface 27 is against the end of the rib 24 and the inner edge of the plate which forms the cam-surface 28 is concentric with 5 and forms a continuation of the inner side of the rib. When the sinker cam-ring is reversed, the plate 29 is shifted by reason of the friction between the plate and the sinkers from the position shown in Fig. 1 to the position shown in Fig. 3, the movement of the 10 plate and its position being determined by the shape of the guiding-slots 31. This movement of the plate brings the cams 27 and 28 into position to retract and advance 15 the sinkers and brings the cam-surface 25 against the end of the rib 24 and cam-surface 26 into position concentric with the rib 24. When the cam-ring is again reversed, the 20 plate is shifted into the position of Fig. 1, and thus as the cam-ring reciprocates the 25 cams are shifted automatically to vary the points at which the sinkers are retracted and advanced. The cam-surfaces on the plate 29 are so arranged with relation to the knitting-wave that the sinkers are withdrawn at 30 the point where the needles are drawing the new loops and are advanced to overlie the loops as the needles rise through them, the cam-surface 25 retracting the sinkers on the 35 front side of the knitting-wave and cam-surface 26 advancing the sinkers on the rear side of the wave as the wave travels from right to left and the cam-surface 27 retracting the sinkers on the front side of the knitting-wave and the cam-surface 28 advancing the sinkers on the rear side of the wave as the wave travels in the opposite direction, or from left to right.

In order that the outward movement of 40 the sinkers may be varied, means are provided for varying the shape of the guiding-slots, which determine the positions of the cam-plate 29. This means consists of a plate 30^a, radially adjustable in the sinker cam-ring and provided with edges 31^a, which may 45 be brought by the outward adjustment of the plate 30^a into position to form the inner edge of the guiding-slots, as indicated in Fig. 7. If the edges 31^a are inside the inner edge 50 of the slots 31, then the edge of the slots 31 determine the outer positions of the cams 25 and 27. By moving the plate 30^a radially outward the edges 31^a may be adjusted so 55 that they will form the inner edges of the guiding-slots and determine the outer positions of the cams 25 and 27. The plate 30^a is held in adjusted position by a screw 32^a.

The sinker cam-ring is connected with the cam-cylinder through a stud 33^a, rising from 60 the cam-cylinder, and arranged to be engaged by two adjustable screws 34^a on the cam-ring. These screws may be adjusted to determine the relation between the sinker-cams and the knitting-cam and may be adjusted to prevent any lost motion between 65

the cam-cylinder and sinker cam-ring or may be adjusted to allow of lost motion, if desired. It is preferred, however, to have no lost motion between the cam-cylinder and sinker cam-ring, as with the parts thus adjusted there are no sudden jars or shocks due to the sudden engagement of a moving part with a comparatively heavy part, such as would occur were there lost motion between the sinker cam-ring and the part which drives it. 70

There is no lost motion in the construction described between the knitting-cam and the part which rotates it; nor is there lost motion between the sinker cam-ring and the part which drives it. The lost motion which causes the two sets of sinker-operating cams to be alternately brought into and out of active position takes place between the sinker cam-ring and the light plate carrying the 85 cams. The machine may be run at high speed, therefore, during reciprocating knitting without injury to the parts.

The shifting of the plate which carries the sinker-cams circumferentially of the cam-ring is caused by relative movement between the sinker cam-ring and a part with which the plate is frictionally engaged, this part being the sinkers in the construction shown. This movement of the plates causes one set of 90 cams to be moved radially to bring them into active position and the other set of cams to be moved radially to carry them out of action. It will also be noted that the relative movement of the plate is rearward with relation to the travel of the sinker cam-ring, while the cams are so arranged that the point at which the sinkers are advanced is shifted forward by this rearward shifting of the cam-carrying plate. This causes the advance of 95 the sinker on the proper side of the knitting-wave without lost motion between the knitting-cam carrier and the part which rotates it and without lost motion between the sinker cam-ring and the part which operates it. 100

As the knitting-wave travels along the series of needles the thread must be led to the needles in advance of the knitting-point, and since the wave is in fixed relation to the cam-cylinder and travels back and forth along the series of needles during reciprocating knitting it follows that the thread should be led to the needles from first one side and then the other of the knitting-wave at such time. 115 This is accomplished by the employment of two thread-guides 32 and 33, formed in the latch-ring 34 and provided with guiding-surfaces 35 and 36, over which the thread is drawn as it passes to the needles, the surfaces 120 being arranged at substantially right angles to the line of travel of the thread as it passes therefrom to the knitting-point, so that there is no tendency for the thread to slide laterally over said surface. The two thread-guides 130

are connected by a slot 37, which serves to direct the thread from one guide to the other.

During reciprocating knitting the thread is led over surface 35 as the cam-cylinder moves from left to right, and during the travel of the knitting-wave along the active needles the thread runs to the needles in a line at right angles to the surface 35. When the knitting-cam has passed the active needles, the thread leads from the last active needle to the thread-guiding surface 35, and as the thread-guide travels away from the last active needle the thread will draw over the surface 35 at an angle which will grow more acute as the cam-cylinder continues its movement until the thread slides up the incline 35 and into the slot 37, along which it will travel until it enters the guide 33. Now when the cam-cylinder reverses and travels from right to left the thread will run through the guide 33, and when the guide has passed the inactive needles and the active needles begin to be operated by the knitting-cam the thread will run over the surface 36, as indicated in Fig. 2. During the latter part of the stroke of the cam-cylinder in this direction the thread will slide off the incline 36 and be guided by the slot 37 into the guide 32 preparatory to the next stroke of the cam-cylinder from left to right.

The machine may be provided with devices for transferring individual needles from the active to the inactive series, and vice versa, during the narrowing and widening when forming the heel or toe of a stocking, and with devices for throwing the needles not used on the heel or toe out of and into action, as is usual in automatic knitting-machines, and these devices may be of any well-known construction.

What I claim as my invention, and desire to secure by Letters Patent, is—

1. In a knitting-machine the combination, with the sinkers, of sinker retracting and advancing cams shifted through the action of the sinkers to vary the points at which the sinkers are operated, substantially as described.

2. In a knitting-machine the combination, with the sinkers, of shifting sinker-operating cams for retracting and advancing the sinkers shifted by their engagement with the sinkers as the relative movement between the sinkers and operating-cams is reversed, substantially as described.

3. In a knitting-machine the combination, with the sinkers, of a shifting plate provided with two sinker-retracting cams and two sinker-advancing cams, and means for so guiding the plate that it is shifted by its engagement with the sinkers during reciprocating knitting to bring first one set of cams and then the other set into operation, substantially as described.

4. In a knitting-machine the combination,

with the sinkers, of a sinker cam-ring, sinker retracting and advancing cams mounted thereon and shifted circumferentially as the relative movement between the sinkers and cam-ring is reversed, and slots for determining the positions of the sinker-cams, substantially as described.

5. In a knitting-machine the combination, with the sinkers, of a sinker cam-ring, sinker-operating cams mounted thereon and shifted circumferentially as the relative movement between the sinkers and cam-ring is reversed, slots for determining the positions of the sinker-cams, and means for varying the shape of the slots, substantially as described.

6. In a knitting-machine the combination, with a sinker cam-ring, of a shifting plate 29 mounted thereon and provided with cam-surfaces 25, 26, 27 and 28, substantially as described.

7. In a knitting-machine the combination, with a sinker cam-ring, of a shifting plate 29 mounted thereon and provided with cam-surfaces 25, 26, 27 and 28, slots in the ring for guiding the plate, and means for varying the shape of the slots, substantially as described.

8. In a knitting-machine the combination of a series of needles, means for causing a knitting-wave to travel back and forth along the series of needles, means for leading the thread to the needles in advance of the knitting-point as the knitting-wave travels, sinkers for holding the fabric as the needles rise, and means operated by the sinkers for shifting the points at which the sinkers are advanced and withdrawn from side to side of the knitting-wave, substantially as described.

9. In a knitting-machine the combination of a needle-cylinder, needles guided therein, a cam-cylinder provided with means for forming a knitting-wave in the needles in fixed relation to the cam-cylinder during reciprocating knitting, sinkers for holding the fabric as the needles rise, and sinker-operating cams moved circumferentially and radially to shift the points at which the sinkers are withdrawn and advanced from side to side of the knitting-point during reciprocating knitting, substantially as described.

10. In a knitting-machine the combination, with a needle-cylinder and needles, of a cam-cylinder provided with a single knitting-cam for drawing down the needles during reciprocating knitting, sinkers for holding the fabric, and a sinker cam-ring provided with sinker-operating cams shifted circumferentially and radially during reciprocating knitting, substantially as described.

11. In a knitting-machine, the combination with the sinkers and sinker cam-ring, of a plate shifted by relative movement between the sinker cam-ring and a part with which the plate is frictionally connected, and cams for advancing the sinkers moved into

and out of action by the shifting of said plate, substantially as described.

12. In a knitting-machine, the combination, with the sinkers, cams for retracting and advancing the sinkers, means for shifting said cams circumferentially as the relative movement between the sinkers and operating-cams is reversed, and means for moving said cams into and out of active position as they are shifted, substantially as described.

13. In a knitting-machine, the combination, with the sinkers, of a shifting plate, two sets of sinker-operating cams carried thereby, and means for bringing first one set of cams and then the other set into operation by the shifting of said plate, substantially as described.

14. In a knitting-machine, the combina-

tion, with the sinkers and sinker cam-ring, of sinker-operating cams, movably mounted in the cam-ring, means for shifting the cams rearward of the cam-ring as its motion is reversed and varying the positions of the cams to shift forward the point at which the sinkers are advanced, substantially as described.

15. In a knitting-machine, the combination, with the sinkers, of sinker-operating cams shifted circumferentially and radially as the relative movement between the cams and sinkers is reversed, substantially as described.
